(57) **CLAIM**

I claim the ornamental design for a lint catching device, as shown and described.

DESCRIPTION

FIG. 1 is a perspective view showing my design of the lint catching device;

FIG. 2 is an exterior perspective view of the first half thereof;

FIG. 3 is a perspective view composed of the first and second halves which are shown in a transparent form for illustrative purpose to reveal the details thereof;

FIG. 4 is a perspective view of the interior of the first half thereof;

FIG. 5 is a front elevational view of the interior of the first half thereof;

FIG. 6 is a rear elevational view of the exterior of the first half thereof;

FIG. 7 is a left elevational view of the first half thereof;

FIG. 8 is a right elevational view of the first half thereof;

FIG. 9 is a top plan view of the first half thereof;

FIG. 10 is a bottom plan view of the first half thereof;

FIG. 11 is a perspective view of the interior of the second half thereof;

FIG. 12 is a front elevational view of the interior of the second half thereof;

FIG. 13 is a rear elevational view of the exterior of the second half thereof;

FIG. 14 is a left elevational view of the second half thereof;

FIG. 15 is a right elevational view of the second half thereof;

FIG. 16 is top plan view of the second half thereof; and,

FIG. 17 is a bottom plan view of the second half thereof. The shade lines in the figures show contour and not surface ornamentation. The dot-dash broken lines illustrate portions of the lint catching device and form no part of the claimed design.

Further, the surfaces between the broken lines and the solid lines form no part of the claimed design.

1 Claim, 17 Drawing Sheets
